UNITED STATES PATENT OFFICE.

JONAS ALBERT SPARKS, OF ELK CITY, AND LESLIE C. WATERS, OF COLUMBUS, KANSAS.

DRYING AND AERATING MACHINE.

1,202,445.

Specification of Letters Patent. Patented Oct. 24, 1916.

Application filed May 19, 1915. Serial No. 29,179.

To all whom it may concern:

Be it known that we, JONAS ALBERT SPARKS and LESLIE C. WATERS, citizens of the United States, residing at Elk City and 5 Columbus, respectively, in the counties of Montgomery and Cherokee, respectively, and State of Kansas, have invented certain new and useful Improvements in Drying and Aerating Machines, of which the following 10 is a specification.

This invention contemplates an improved drying and aerating machine especially designed for use in connection with the processes of dry and other cleaning.

15 The invention has as its primary object to provide a machine adapted, through the medium of centrifugal action, to thoroughly expel all soils, dirt and other foreign matter, and to dry and expel all of the cleansing 20 fluid or commodities from the articles placed within the machine and, to at the same time thoroughly aerate the said articles so that the odor of the said fluids or commodities will be entirely removed therefrom.

25 The invention has as a further object to provide a machine of this character so constructed that in the normal operation thereof, air currents within the machine will be automatically set up to thus effectually 30 aerate the articles placed within the machine.

A still further object of the invention is to provide a machine so constructed that the moving air currents within the machine in 35 the normal operation thereof will tend to induce an inflow of fresh air currents which latter air currents will be directed immediately toward or against the articles placed within the machine, so that all odors of any 40 cleaning fluids and commodities clinging to the articles will be removed therefrom.

A further object of the invention is to provide an improved, rotatably mounted basket adapted to receive the articles to be 45 dried and of such character as to attain maximum results upon the said articles, through the force of centrifugal action, when rotated at any given speed.

The invention has as a further object in 50 this connection to provide an improved mounting for the basket so constructed and arranged that the basket may be easily rotated and that a ready access may also be had to the basket for the purpose of placing articles therein or removing the articles 55 from the basket. And the invention has as

a still further object to provide an improved device of this character which will be durable in use, and which may be placed upon the market at moderate cost.

Other and incidental objects appear as the description proceeds and in the drawings wherein we have illustrated the preferred embodiment of the invention and wherein similar reference characters designate corresponding parts throughout the several views,

Figure 1 is a perspective view of our improved device, Fig. 2 is a sectional view more particularly showing the construction and mounting of the several elements of the device, Fig. 3 is a perspective view particularly showing the shaft supporting the spider carried by the basket employed, and Fig. 4 is a fragmentary sectional view particularly showing the mounting of the basket.

In the preferred embodiment of our invention as illustrated in the drawings, we employ a base which includes a preferably 80 rectangular platform 10 having sills 11 to which are secured cross-pieces or boards 12. Mounted upon the platform 10 is a block 13 at one end of which is arranged a vertically disposed and transversely extending block 14. 85

Rising from the block 13 at its extremity opposite the block 14 are spaced vertically disposed posts 15 and 16 respectively, the said posts being arranged substantially parallel and being secured to the block 13. 90 Connecting the posts 15 and 16 at the upper extremities thereof is a plate 17 and bearing over the said plate and arranged within the lines of the post 15 is a brace strap 18, the said strap and plate being held in position 95 by screws 19 or other suitable fastening devices. The strap 18 is, at its free end suitably connected to the block 13 as more particularly shown in Fig. 1 of the drawings and is thus adapted to rigidly support the said post. Extending between the post 16 and the block 14 is a cross-piece 20 disposed in substantial parallel relation to the block 13 and having its extremities respectively secured, in any suitable manner, to the post 16 and to the said block. Mounted upon the block 13 and supporting the cross-piece 20 intermediate its ends, is a post 21 which is, as will be observed upon reference to Fig. 100 2 of the drawings, arranged in spaced substantially parallel relation to the block 14.

105 Arranged to seat flatly against opposite

110

side edges of the cross-piece 20 and extending between the posts 16 and 21 respectively, are closure plates 22. The plates 22 are provided with laterally directed longitudinally extending flanges 23 seating flatly against the adjacent upper face of the block 13 and are detachably held in position by screws or other suitable fastening devices as clearly illustrated in Fig. 1 of the drawings. Mounted upon the base thus formed, is a driving mechanism for the basket employed. This mechanism includes a tooth wheel 24 arranged between the posts 15 and 16 and mounted upon a shaft 25 which is journalled within suitable sleeves 26 carried by the posts 15 and 16 respectively. Connected to the outer terminal of the shaft 25 is a crank 27 which is provided with a handle 28. Mounted upon the posts 16 and 21 respectively and arranged substantially parallel to the block 13 is a drive shaft 29 which is journalled, adjacent its extremities in suitable sleeves 30 carried by the said posts. Keyed upon the shaft 29 at one extremity, is a pinion 31 while a beveled gear 32 is keyed to the opposite extremity of the shaft.

Mounted upon the cross-piece 20 to abut at one side with the post 16 is a preferably cylindrical casing 33 which is open at its upper end and the bottom wall 34 of which is secured to the said cross-piece in any suitable manner. Formed on the bottom wall, adjacent one side of the casing is a discharge spout 35 while the said wall at a point centrally thereof is provided with a suitable opening which is surrounded by an upstanding annular collar 36 projecting laterally into the casing as more particularly shown in Fig. 2 of the drawings. The purpose of this collar will presently appear.

Arranged within the casing 33 is a preferably cylindrical basket designated as a whole by the numeral 37. The basket 37 is preferably provided with a solid bottom wall 38 and a foraminous circular wall 39, the wall 39 being formed with circumferentially spaced series of vertically arranged openings, as clearly shown in Fig. 2 of the drawings. Preferably these openings are relatively small in diameter and are arranged in close spaced relation, this also being for a purpose which will presently appear. Formed on the wall 39 at the open end of the basket is a substantially frusto-conical rim 40.

Seating against the outer face of the bottom wall 28 of the basket is a shaft supporting spider 41, best shown in Fig. 3 of the drawings. This spider 41 includes a preferably cylindrical body portion 42 arranged centrally of the wall 38 and from which extend quadrantly spaced arms 43. The arms 43 at the outer extremities thereof are provided with laterally directed lugs 44

seating against the circular wall 29 of the basket to be secured thereto in any suitable manner. Formed on the body portion 42 and arranged axially of the basket is a cylindrical socket or sleeve 45 which is provided with a radially disposed set screw 46.

Detachably seating at one extremity within the socket 45 is the vertically arranged shaft or stem 47 of the basket 37, which is arranged axially of the basket and is rigidly connected therewith through the medium of the set screw 46. Detachably mounted upon the shaft 47 and arranged to abut the socket 45 is a substantially frusto conical thrust collar 48 which is preferably connected with the shaft to rotate therewith through the medium of a radial set screw 49 carried by the collar. The collar 48 is arranged to coact with an anti-friction bearing 50 seated within a suitable recess formed in the adjacent upper face of the cross-piece 20 as more particularly shown in Fig. 2 of the drawing.

The anti-friction bearing 50 is shown in detail in Fig. 4 of the drawings and it will be observed that the said bearing includes an annular substantially cap shaped casing 51 within which are arranged coacting bearing rings 52 and 53 respectively. Interposed between the said rings are anti-friction devices 54 while the casing is formed with an inwardly extending annular flange 55 arranged to maintain the several elements of the bearing in assembled relation. It will now be observed that the ring 53 is substantially frusto-conical in contour and is adapted to freely receive the shaft 47 to coact with the thrust collar 48. Thus, the bearing 50 will freely support the entire load of the basket and the contents thereof, it being observed that the said basket is mounted concentrically within the casing 33 with the shaft 47 projecting freely through the collar 36 and extending freely through the cross-piece 20. Preferably, the shaft 47 at its free end is detachably received within a suitable bearing sleeve 56 mounted within the block 13, so that the said shaft will be rigidly supported in operative position.

Removably keyed upon the shaft 47 is a beveled pinion 57 arranged to coact with the beveled gear 32 and as will now be readily understood, the basket 37 may thus be readily rotated by turning the crank 27. The ratio of the gearing between the tooth wheel 24 and the beveled pinion 57 may, of course, be varied at will, but is preferably so formed that the basket 37 will be rotated at a relatively high rate of speed, while the crank 27 will turn but slowly. Thus, with comparatively small effort on the part of the operator, maximum results may be attained through the centrifugal action set up within the basket 37 and in this connection attention is directed to the fact that in mak-

ing the openings within the circular wall 39 of the basket relatively small and arranging the openings in close spaced relation, it has been found in use, that in providing a relatively large number of such openings within the said circular wall, that a basket so formed will efficiently operate, when rotated at a relatively high rate of speed, to effect a thorough drying of any articles placed 10 within the basket.

Closing the open end of the casing 33 is a frusto-conical lid or cover 58 which, at its periphery is provided with an annular laterally directed flange 59 adapted to frictionally engage the wall of the casing to provide a tight joint between the casing and the lid. Mounted within the lid 58 and opening through the apex thereof is an axially arranged tubular air-spout or inlet 60, the inner terminal of which, when the lid is applied to the casing, is arranged, as will be observed upon reference to Fig. 2 of the drawings, to extend vertically within the casing and terminates laterally upon one side of and above the open end of the basket 37. Connected to the lid 58 in any suitable manner, is a handle 61 which is arranged to extend over the outer end of the spout 60 to provide a guard therefor.

Having thus described the construction of the invention, its operation will now be more fully set forth. It will be observed that the basket 37 is supported in spaced relation to the casing 33 to provide an air space between the bottom of the basket and the bottom wall 34 of the casing and to also provide an annular air space surrounding the basket. In use, the articles to be dried and aerated, are placed within the basket and the basket is rotated through the medium of the crank 27 or other power device. The centrifugal action thus set up within the basket will force any moisture within the said articles out through the openings in the wall 39 of the basket to be discharged through the spout 35 of the casing 33, attention being particularly directed in this connection, to the fact that the collar 36 is adapted to prevent any moisture or fluids from coming in contact with the shaft 27 or the bearing 50, thus eliminating the necessity for the use of a packing gland between the casing and the said shaft. The rim 40 of the basket being imperforate, will prevent any moisture extracted from the said articles from being thrown upwardly by the radial movement of the basket to be discharged at the open end thereof. When the basket 37 is thus rotated, the movement thereof will set up an upward draft within the casing in the annular space between the circular wall of the basket and the casing, which draft will flow or move upwardly within the casing to strike the frusto-conical lid 58. This upward draft upon striking the lid 58 will be directed

thereby toward the apex of the lid to be thence directed downwardly and inwardly into the open end of the basket to flow freely past the open end of the air spout 60. This flow of air within the casing 33 will tend to 70 produce a partial vacuum within the basket 37 so that odors clinging to the articles placed within the said basket will be drawn therefrom outwardly and into the annular space between the casing and the circular 75 wall of the basket. The draft in flowing over the inner open end of the fresh air spout 60 will also create a partial vacuum within the said spout to cause fresh air to be drawn in through the spout when it will 80 be directed thereby immediately toward or against the articles placed within the basket. Such fresh air being thus brought into intimate contact with the articles being dried, will effectually aerate the said articles to practically remove all of the odors of any liquids or acids previously used in the cleaning of the articles.

It will therefore be seen that we provide a device adapted to simultaneously dry and 85 aerate the articles placed therein, and which will be found durable and thoroughly efficient in use.

Having thus described our invention, what we claim and desire to secure by Letters Patent is:—

1. A device of the character described including a casing provided with a discharge opening, a basket rotatably mounted within the casing and provided with a perforation, 100 a cover for the casing, a spout opening through the cover and depending entirely within the top and bottom lines thereof toward the basket, and means for rotating the basket to set up an inflowing current of air 105 through the spout into the basket to be drawn through the perforation therein and expelled through said discharge opening.

2. A device of the character described including a casing provided with a discharge 110 opening, a basket rotatable within the casing and having a perforation formed therein, the interior of the basket being entirely unobstructed, a cover for the casing, a spout opening through the cover and extending 115 toward the basket, and means for rotating the basket to set up an inflowing current of air through said spout into the basket to be drawn through the perforation therein and expelled through the said discharge opening.

3. A device of the character described including a closed casing provided with a discharge opening, a basket rotatable within the casing and provided with a perforation, a 125 spout opening through the casing with its outlet end depending toward the basket and terminating above the upper line thereof, and means for rotating the basket to set up an inflowing current of air through said 130

spout into the basket to be drawn through the perforation therein and expelled through the said discharge opening in the casing.

4. A device of the character described including a closed casing provided with a discharge opening, a basket rotatable within the casing and provided with a perforation, an inlet depending into the casing and of uniform diameter throughout and terminating above the upper line of the basket, and means for rotating the basket to cause currents of air to pass through said inlet into the basket and escape through said basket perforation and the discharge opening in the casing.
- 10 5. A device of the character described in-

cluding a closed casing provided with a discharge opening, a basket rotatable within the casing and provided with a perforation and an annular top sloping downwardly and outwardly, an inlet depending into the casing and terminating above the upper line of the basket, and means for rotating the basket to cause currents of air to pass through said inlet into the basket and escape through said basket perforation and the discharge 20 25 opening in the casing.

In testimony whereof we affix our signatures.
